ALARM DEVICE

Charles Grant Trefethen, Worcester, Mass.

Application April 1, 1933, Serial No. 663,985

14 Claims. (Cl. 116—87)

This invention relates to devices for sounding an alarm when an attempt is made to open a window or door in an unauthorized manner, as by a burglar.

5 It is the general object of my invention to provide improved devices for such purposes whereby a distinctive audible signal will be given when an attempt to open a door or window is made by an unauthorized person. I also provide means by 10 which the alarm device may be rendered inoperative by an authorized person during periods when no alarm is desired.

15 Further features of the invention relate to means by which the device may be rendered inoperative from the outside of the door to which it is attached.

20 My invention further relates to arrangements and combinations of parts which will be herein-after described and more particularly pointed out in the appended claims.

Preferred forms of the invention are shown in the drawings, in which

Fig. 1 is a side elevation, partly in section, 25 showing my alarm device as used in the protection of window openings;

Fig. 2 is a plan view of the device, partially broken away and looking in the direction of the arrow 2 in Fig. 1;

Fig. 3 is an end view of the device, looking in 30 the direction of the arrow 3 in Fig. 1;

Fig. 4 is a partial plan view of the base plate, looking in the direction of the arrow 4 in Fig. 3;

Fig. 5 is a perspective view of the slide bar 35 which controls the trigger and hammer;

Fig. 6 is a perspective view of the member which actuates the slide bar to sound an alarm;

Fig. 7 is a plan view showing the application 40 of my invention for protecting a door opening;

Fig. 8 is an end view of the actuating member, looking in the direction of the arrow 8 in Fig. 7;

Fig. 9 is a plan view of a modified construction to be described;

Fig. 10 is a front elevation thereof, looking in the direction of the arrow 10 in Fig. 9, and

Fig. 11 is an end elevation, partly in section, showing the application of this construction to an outside door.

Referring particularly to Figs. 1 to 6, I have 50 shown my invention as adapted to the protection of window openings. In this form, my alarm device comprises a base plate 10 adapted to be secured to the upper edge of a lower window sash S and permanently secured thereto in a convenient manner, as by screws 11. The alarm mecha-

nism is mounted within a casing 12 slidable in guideways 13 (Fig. 3) in the base plate 10.

The casing 12 is retained in the base plate 10 by a locking arm 14 mounted to rotate with a lock barrel 15 which is positioned in one end of the casing 12 and is operable by a removable key 16. The base plate 10 has a slot 17 to receive the locking arm 14. When the parts are positioned as shown in Figs. 1 and 3, the casing 12 cannot be removed from the base plate 10 without the use of the key 16.

A hammer 20 is pivoted at 21 in the casing 12 and is movable by a spring 22 to strike and explode a cartridge C mounted in a recess or chamber 24 (Fig. 2) and having a vent passage 25 for escaping gases. The hammer 20 is provided with a holding arm or trigger 27 normally seated in a notch 28 (Fig. 5) in a slide bar 30. The bar 30 extends through slots 31 in the end walls of the casing 12 and is supported on studs or cross pins 32 mounted in the casing 12.

At its outer end, the slide bar 30 has a projecting portion 33 having V-shaped notches 34 and 35 in its upper and lower edges. The bar 30 is also provided with a longitudinal recess 36 and with a transverse slot 37, also with a stop pin 38 in one side thereof.

When the locking arm 14 is swung to the dotted line position indicated in Fig. 3, the arm 14 extends into the slot 37 so that the slide bar 30 is held from relative movement in the casing 12 and consequently the hammer 20 cannot be released when the locking arm 14 is in said dotted line position. Stop pins 39 (Fig. 3) limit swinging movement of the locking arm 14 in both directions and the stop pin 38 limits the sliding movement of the bar 30.

An actuating member 40 (Fig. 6) is preferably secured in a recess in a side portion of the upper window sash S' (Fig. 1) and the member 40 is provided with a recess 41 having an upwardly and outwardly inclined upper surface 42 and a depending projection 43. The normal position of the parts is as shown in Fig. 1, with the projection 33 of the slide bar 30 extending into the recess 41 of the actuating member 40.

If the lower sash S is now raised, the upper outer edge portion or corner of the projection 33 of the slide bar 30 will engage the inclined surface 42 and will be pushed to the right thereby (as viewed in Fig. 1), by which movement the longitudinal recess 36 will be moved under the trigger 27, thus releasing the hammer 20 and causing explosion of the cartridge C.

Furthermore, the depending projection 43 of

the actuating member 40 will be received in the notch 34 in the upper side of the slide bar 30, so that further opening movement of the sash S will be effectively prevented after the alarm has 5 been sounded.

In order to re-load and re-set the device, the bar 30 is pushed back to initial position, the key 16 is inserted, and the locking arm 14 is swung to the dotted line position in Fig. 3, thus releasing the casing 12 from the base plate 10. The casing is then removed, the hammer 20 is reset in the position shown in Fig. 1, with the trigger 27 again seated in the notch 28 of the slide bar 30, and a new cartridge C is inserted in the 15 recess or opening 24. The casing is then returned and locked in initial position, the key 16 is removed and the apparatus is again in condition for service.

If it is desired to render the alarm device inoperative at any time, this is readily accomplished by inserting the key 16, turning the lock arm 14 to the left in Fig. 3, thereby releasing the casing 12 and locking the slide bar 30 and thereafter sliding the casing in its guideways far enough to the right in Fig. 1 so that the projection 33 of the slide bar will clear the actuating member 40 in the upper sash S'. The second notch 35 is provided to take care of cases in which it may be desired to protect a member from movement in either of two reversed directions. The actuating member 40 may be substantially varied in form and in the manner and location of its application to the sash S', so long as it provides a cam surface for engagement with the end of the slide bar 30.

In Figs. 7 and 8 I have shown the application of my invention to a door D closing against a door jamb 50. For this purpose the casing 12 is mounted on the side of the door D opposite to the door jamb 50 and the actuating member 51 is attached to the door casing 52.

The actuating member 51 is similar to the member 40 previously described but it is preferably provided with laterally extending ears 53 through which screws 54 may be inserted for securing the member 51 to the door casing.

It is assumed that the alarm device is on the inside of the door, where it cannot be reached by an unauthorized person who must attempt admission by moving the door in the direction of the arrow a in Fig. 7. The device operates to sound the alarm in the same manner as the form of the invention shown in Figs. 1 to 6.

In Figs. 9, 10 and 11 I have shown an adaptation of my invention for use on an outside door D' where a duly authorized person may wish to disable the alarm device from outside the door, so that such a person may effect entrance without sounding the alarm.

For this purpose the casing 60 is mounted on a base plate 61 having a projecting portion 62 supporting a lug or stop 63. The base plate 61 also has a laterally projecting portion 64 having a stud 66 on which a disc 65 is rotatably mounted. The disc 65 has a pin 67 projecting into a slot 68 in one of the guiding flanges 69 of the casing 60.

The hub portion 70 of the disc 65 projects into an opening in the door D' and is provided with a transverse rib 71 extending into a slot 72 in the adjacent end of a rotatable member 73 associated with a lock 74 mounted in the door D' and having a lock plate 75 on the outer face thereof.

This lock 74 may be of any suitable commercial construction, it being merely desirable that one

full revolution of a key in the lock 74 will cause a full revolution of the rotatable member 73, with a corresponding full revolution of the disc 65. Initial rotation of the disc 65 moves the casing 60 along the base plate 61 to an inoperative position.

The flange 69 of the casing 60 is provided with a notch 80 (Fig. 10) which receives the pin 67 of the disc 65 when the disc 65 has made one complete revolution and after the casing 60 has been moved to the right (as viewed in Figs. 9 and 10) until it substantially engages the stop 63.

Having made one complete revolution, the key may then be removed if desired. The stop 63 is so positioned that it is aligned with the slide bar 30 and prevents such movement of the bar as would release the hammer 20 to sound an alarm while the device is in withdrawn position.

By this construction it is possible for an authorized person to withdraw the alarm device from operative position while said person is located at the outer side of the door D'.

From the preceding description of several forms of my invention, it will be evident that I have provided an extremely simple and reliable 100 device by which a distinctive and audible alarm will be sounded whenever an attempt is made to open a door or window or other protected opening.

Having thus described my invention and the advantages thereof, I do not wish to be limited to 105 the details herein disclosed, otherwise than as set forth in the claims, but what I claim is:—

1. An alarm device comprising a base plate to be mounted on a supporting member, a casing movably mounted on said base plate, alarm mechanism mounted in said casing, an actuating member to be mounted on a second supporting member, relative movement of said supporting members causing said actuating member to engage and move an element of said alarm mechanism to thereby initiate an alarm, said casing being manually slidable on said base plate to remove said alarm mechanism to an inoperative position, and means to lock said casing in operative position on said base plate. 110

2. An alarm device comprising a base plate to be mounted on a supporting member, a casing movably mounted on said base plate, alarm mechanism mounted in said casing, an actuating member to be mounted on a second supporting member, relative movement of said supporting members causing said actuating member to engage and move an element of said alarm mechanism to thereby initiate an alarm, said casing being manually slidable on said base plate to remove said alarm mechanism to an inoperative position, and means to prevent operation of said alarm mechanism when said casing is removed from operative position. 120

3. An alarm device comprising a base plate 135 to be mounted on a supporting member, a casing movably mounted on said base plate, alarm mechanism mounted in said casing, an actuating member to be mounted on a second supporting member, relative movement of said supporting members causing said actuating member to engage and move an element of said alarm mechanism to thereby initiate an alarm, said casing being manually slidably on said base plate to remove said alarm mechanism to an inoperative 140 position, and a single means effective to lock said casing in operative position on said base plate and to lock said alarm mechanism in said casing when said casing is unlocked.

4. An alarm device comprising a base plate to 150

- be mounted on a supporting member, a casing movably mounted on said base plate, alarm mechanism mounted in said casing, an actuating member to be mounted on a second supporting member, relative movement of said supporting members causing said actuating member to engage and move an element of said alarm mechanism to thereby initiate an alarm, said casing being manually slidable on said base plate to remove said alarm mechanism to an inoperative position, and means to lock said casing in operative position on said base plate, said latter means comprising a lock fixed to said first supporting member on the opposite side from said alarm device, and connections from said lock to said casing through which said lock is rendered effective to slide said casing in said base plate. 80
- 5 5. An alarm device comprising a base plate to be mounted on a supporting member, a casing movably mounted on said base plate, alarm mechanism mounted in said casing, an actuating member to be mounted on a second supporting member, relative movement of said supporting members causing said actuating member to engage and move an element of said alarm mechanism to thereby initiate an alarm, said casing being manually slidable on said base plate to remove said alarm mechanism to an inoperative position, and a single means operative in one position to lock said casing to said base plate and in another position to lock said alarm mechanism against operation in said casing. 85
- 10 6. An alarm device comprising a base plate to be mounted on a supporting member, a casing movably mounted on said base plate, alarm mechanism mounted in said casing, an actuating member to be mounted on a second supporting member, relative movement of said supporting members causing said actuating member to engage and move an element of said alarm mechanism to thereby initiate an alarm, said casing being manually slidable on said base plate to remove said alarm mechanism to an inoperative position, and a locking means alternately operative to lock said casing to said base plate or to lock said alarm mechanism against operation in said casing. 90
- 15 7. An alarm device comprising a base plate to be mounted on a supporting member, a casing movably mounted on said base plate, alarm mechanism mounted in said casing, an actuating member to be mounted on a second supporting member, relative movement of said supporting members causing said actuating member to engage and move an element of said alarm mechanism to thereby initiate an alarm, said casing being manually slidable on said base plate to remove said alarm mechanism to an inoperative position, and means to lock said casing in operative position on said base plate, said latter means comprising a lock fixed to said first supporting member on the opposite side from said alarm device, and connections from said lock to said casing through which said lock is rendered effective to slide said casing in said base plate, and means on said base plate effective to render said alarm mechanism inoperative when said casing is moved to extreme inoperative position. 95
- 20 8. An alarm device comprising a base plate to be mounted on a supporting member, a casing movably mounted on said base plate, alarm mechanism mounted in said casing, an actuating member to be mounted on a second supporting member, relative movement of said supporting members causing said actuating member to engage and move an element of said alarm mechanism to thereby initiate an alarm, said casing being manually slidable on said base plate to remove said alarm mechanism to an inoperative position, and means to lock said casing in operative position on said base plate, said latter means comprising a lock fixed in said casing and operable by a removable key and having a portion co-acting with said base plate. 100
- 25 9. An alarm device comprising a base plate to be mounted on a supporting member, a casing movably mounted on said base plate, alarm mechanism mounted in said casing, an actuating member to be mounted on a second supporting member, relative movement of said supporting members causing said actuating member to engage and move an element of said alarm mechanism to thereby initiate an alarm, said casing being manually slidable on said base plate to remove said alarm mechanism to an inoperative position, and means to lock said casing in operative position on said base plate, said latter means comprising a lock fixed to said first supporting member on the opposite side from said alarm device, and connections from said lock to said casing through which said lock is rendered effective to slide said casing in said base plate, and means on said base plate effective to render said alarm mechanism inoperative when said casing is moved to extreme inoperative position. 105
- 30 10. An alarm mechanism comprising a casing, a cartridge mounted therein, a spring-actuated hammer pivoted in said casing, a trigger for said hammer, a slide bar in said casing normally holding said trigger and hammer from operative movement, and cam means to move said slide bar and release said trigger to sound an alarm, the operating movement of said cam means being in a direction substantially perpendicular to the releasing movement of said slide bar. 110
- 35 11. The combination in an alarm device as set forth in claim 10, in which manual means is provided to lock said slide bar from longitudinal movement. 115
- 40 12. The combination in an alarm device as set forth in claim 10, in which said casing is mounted on a base plate and in which manual means is provided alternately effective to lock said casing to said base plate or said slide bar in said casing. 120
- 45 13. An alarm mechanism comprising a casing, a cartridge mounted therein, a spring-actuated hammer pivoted in said casing, a trigger for said hammer, a slide bar in said casing normally holding said trigger and hammer from operative movement, and cam means to move said slide bar and release said trigger to sound an alarm, said slide bar and cam means maintaining locking relation after movement of said slide bar by 125 said cam means. 130
- 50 14. An alarm device comprising a base, an alarm mechanism supported by said base, an actuating member, and a lock effective to secure said alarm mechanism in a single predetermined operative position on said base, said alarm mechanism being freely movable to an inoperative position on said base when unlocked. 140
